United States Patent Office.

WASHINGTON H. TUCKER, OF SUNMAN, INDIANA.

Letters Patent No. 80,684, dated August 4, 1868.

IMPROVEMENT IN WAGON-BRAKES.

The Schedule referred to in these Letters Patent and making part of the same.

TO ALL WHOM IT MAY CONCERN:

Be it known that I, WASHINGTON H. TUCKER, of Sunman, in the county of Ripley, and State of Indiana, have invented new and useful Improvements in Wagon-Brakes; and I do hereby declare that the following is a full, clear, and exact description thereof, reference being had to the accompanying drawing, making part of this specification.

My invention relates to mode of constructing the brake-blocks, and to the arrangement of the device for operating the brakes of spring-wagons, in a manner to prevent the strain upon the springs when the brakes are applied to the wheels.

Figure 1 is a side elevation of a wagon having my improvements in brakes applied thereto. The wheels on one side are left off, and a part of the bed is cut away, in order to show more clearly the construction and arrangement of the device.

Figure 2 is a view of the wagon inverted.

Figure 3 shows in detail the construction of the brake-blocks E.

Similar letters of reference indicate corresponding parts in the several figures.

The following description will enable skilled artisans to make and use my invention.

The brake-blocks E are composed of the India-rubber blocks S, and the clamp formed by the two bent metal plates R, the edges of which overlap each other on the back of the block S, as shown in fig. 3. This arrangement of the clamping-plates R is made necessary in order that they may be tightened on the blocks S. The blocks S have a flange projecting from the sides of their faces, to shield the edges of the clamp-pieces R from coming in contact with the wheels. These brake-blocks are attached to the ends of the bent rods F, and are secured thereto by a nut on the end of the rod, on which a screw is cut, in order to tighten the plates R on the block S, to hold it firmly. This mode of constructing the brake-blocks enables me to replace the blocks S with great facility, when required.

The rods F are bent to the proper form to bring the blocks E in the proper relation to the wheels, and are hung in suitable bearings to the under side of the wagon-body, as shown. A rod, P, which may be a single rod, bent as shown, or it may be two rods linked together in the middle, has its ends attached to the arms of rods F near the brake-blocks. A strap of leather, N, is attached to the middle of rod P, and passes back around a sheave or roller, O, that is hung to revolve in a bracket attached to the rear axle. The other end of strap N is attached to a rod, M, that has a screw cut on the other end. The screw-end of rod M passes through a bar or nut on the ends of the double rod L, and the latter is connected by a strap of leather, K, to the lever J, just below the bed-bottom. The lever J has its fulcrum at the lower end in brackets attached to the under side of the bed-bottom, as shown, and the upper end passes up through a slot in the bottom of the bed, in convenient position to be actuated by the foot of the driver.

A notched strap of iron attached to the bottom of the bed serves to hold the lever in any desired position. A short lever, G, is attached to the end of each of the rods F, where they meet under the middle of the bed, and are both connected, by a spiral spring, H, to the bottom of the bed, as shown, for the purpose of keeping the brakes off the wheels when not in use.

The object of having the brake-blocks E attached to separate rods F is to provide for equal pressure of the blocks upon the wheels, regardless of the position of the vehicle, as, when the vehicle is descending an uneven road, such as would twist it much, if the rods F were in one piece, the blocks could not be brought with equal pressure on the wheels.

The brakes are actuated by pressing the lever J forward with the foot, which draws the blocks E back against the wheels. The tendency of the strain upon the straps K N and rods L M is to draw the bed A of the wagon backward, but this is counteracted by the action of the wheels upon the brake-blocks, which is to thrust the bed forward.

The arrangement of the double rod L, carrying the nut to receive the screw of rod M, enables me to shorten the rod in case the straps K and N stretch, by which they may be kept taut, and in proper condition to bring the brake-blocks with sufficient force against the wheels.

Having thus fully described my invention, what I claim as new, and desire to secure by Letters Patent, is—

The blocks E, rods F and P, straps K and N, sheave O, rods L M, spring H, and lever J, all constructed and arranged substantially as and for the purpose set forth.

WASHINGTON H. TUCKER.
